William Myers of Washington County, Maryland
Sellers' Patent.

The Schedule referred to in those Letters Patent and making part of the
same containing a description in the words of the said William
Myers himself of his improvement in the machine for drawing Gun Stock.

Be it known that the said William Myers of Washington County State
of Maryland have made an improvement in the machine for draw-
ing Gun Stock, which is described as follows.

The improvement consists of the platform and Standard to move the
Gun Stock; the box, and the bellows, to blow away the dust.

The platform is about two feet in front and seven feet behind; there
are three distinct partitions, each about two feet. The platform is
supported by four or more timberous supports, resting on the floor of
the gun mill. There are two box, which make inclosures of the
machine, and one which works as a receiver for moving off the ends of
the Gun Stock. These two, are attached to and worked by a com-
mon gun mill wheel above them. A bellows having two pipes, one
set above the platform on which the Gun Stock are placed not touch-
ing it, but having room for the stuff to pass under.

This bellows is of a diameter of twelve and one-half inches, having two pipes, one
for each end working lengthwise for blowing away the dust and in-
ward by the wind of the gun mill. Operation. The Stock being
set marked off is laid on the board, which the gun mill turns
into a circle. The improvement which I claim and desire
to be secured by letter Patent and before described is that of moving
gun stock, particularly the platform on which they are placed, the ar-
rangement of the box for moving them and the bellows for blowing
away the dust. The full illustration of my invention refer to
the model and drawing of the same deposited in the Patent office.

In testimony whereof I have caused to be signed my name before
me witness the 24th day of October 1832

Witnessed "Wm. H. Ward"
